JUSTIFYING MECHANISM FOR TYPE-WRITERS AND THE LIKE

András Goy, Budapest, Hungary; vested in the Alien Property Custodian

Application July 18, 1940, Serial No. 346,228
In Hungary July 18, 1939

3 Claims. (Cl. 197—84)

The present invention relates to a justifying device used on typewriting machines and the like which, by altering the length of the feed movement of the paper carriage, i. e. by a graduated spacing of the characters in a line, completely justifies the lines of a document so that all the lines have a desired equal length and therefore, the ends of the lines adjacent the right hand margin of the document form a straight vertical line. When using a device according to the invention the material is first typewritten with equal letter spacing feed movements, whereby the right hand end of each line generally does not agree with the desired length of the line. After ascertaining the increases and decreases respectively required for compensating the length of lines, the material is re-typed on a clean sheet, during which the required extensions and shortenings of the feed movements are effected in each line so that the right hand ends of the typewritten lines of the finished written document lie in a vertical straight line.

In known devices of this kind the paper carriage and the letter spacing rack bar of the carriage are shiftably arranged relatively to each other in the attainment of this result. In such prior devices, the rack bar mounted on the paper carriage is shifted with regard to the frame of the machine through feed movements of equal length by an escapement device of usual construction. The distance travelled by the paper carriage is altered in accordance with the relative displacement between the paper carriage and the rack bar. If, during writing of each character and during depression of the space bar, the paper carriage is shifted relatively to the rack bar towards the left, for instance, about $\frac{1}{10}$ mm. (looking at the typewriting machine from the front) each feed movement of the paper carriage will be $\frac{1}{10}$ mm. larger than the corresponding feed movement of the rack bar and the entire line will be longer by as many tenths of millimetres as feed movements performed in this line. If, however, during writing of each character and during depression of the space bar, the paper carriage is moved $\frac{1}{10}$ mm. towards the right, then each feed movement of the paper carriage will be $\frac{1}{10}$ mm. shorter than the corresponding feed movement of the rack bar of the carriage. The entire line then will be shortened by as many tenths of millimetres as there have been feed movements that have been performed in this line.

In known devices of this kind, on the one hand, the gradual displacement between the paper car-

riage and the rack bar cannot be effected with the required exactness and, on the other hand, a uniform margin at the left hand edge of the written document is not obtained under all circumstances.

Now, the object of this invention is to provide a device for compensating the margin of the lines which ensures a straight margin at both sides of the written document, by the use of simple constructional means and by a simple operation, the lengthenings and shortenings, respectively, of the feed movements preferably being uniformly distributed over the entire length of the line.

15 The object is obtained, according to the present invention, by connecting an actuating member, effecting an additional movement of the paper carriage, to a control member which may be adjusted, on the one hand, in accordance

10 with the various differences in the length of the line and, on the other hand, in accordance with the length of the line. According to a particularly advantageous modification of the invention, the control member is operatively connected

20 to the device for setting the margin of the machine and may be adjusted on said device. Hereby the exactness and reliability of adjustment is improved and the manipulation substantially facilitated.

25 30 In the accompanying drawings, some constructions according to the invention are shown by way of example.

In these drawings:

Fig. 1 is a diagrammatic view serving to explain the operation of the machine,

Fig. 1 diagrammatically shows a printed line I. The vertical dot-and-dash gauge lines I and II, respectively, indicate the beginning and the end, respectively, of the desired length of the line to which the machine is to be adjusted by the so-called devices for setting the margin. Suppose that in the first printing, the line I of the text extends beyond the gauge line II for the distance a . If now line I with the same number of letters or characters is to end at the gauge line II, then in making the second printing the line must be shortened for the distance a , i. e. the line must be compensated. This amount a of compensation, as will be explained later on, is uniformly distributed over all the feed movements of the line by the device according to the invention and each feed movement will be shortened for a corresponding small amount so that upon the second printing, the line I having the same number of letters or characters it had with the first printing, will exactly fill the space between the gauge lines I and II.

Line 3, due to its contents, results upon the first printing, in a line which is shorter by the amount " a " than the desired length, and therefore, must be extended or lengthened by this amount " a " when making the second printing if the end of the line is to coincide with the gauge line II. According to the invention, the amount " a " of compensation is, as will be explained later on, uniformly distributed over the individual feed movements of the line and each feed movement of this line will be lengthened for a corresponding small amount, so that in the second printing the line 3 having the same number of characters or letters, is extended or lengthened for the amount " a " and will end at the gauge line II.

The same is true for the lines 5 and 7 which have a greater length determined by a corresponding adjustment of the device for setting the margin. This desired length of line is indicated by the gauge lines III and IV. In these longer lines 5 and 7 the amount to be compensated, i. e. the amount " a ," for which, in the second printing, the line 5 is to be shortened and the line 7 is to be lengthened or extended, is distributed over a greater length of line having more feed movements. It is, therefore, evident that with the same amount " a " of compensation a smaller amount of displacement for each feed movement is required when writing

the long lines 5 and 7 than when writing the relatively short lines 1 and 3, respectively.

In the examples subsequently to be described, the invention is explained in connection with a simple typewriting machine of usual construction in which a paper carriage 10 is displaceably guided upon rails 12 provided on the frame 9 of the machine. The printing mechanism, in the present case, type levers 200 driven by key levers 201, is mounted in the machine frame 9 (Fig. 5). By depressing one of the key levers 201 the corresponding type lever 200 is swung and the letter or character carried by this type lever is printed upon the paper arranged around the platen 202. A shoulder 203 of the type lever 200 acts upon a universal bar 204, whereby, by way of intermediate members 205, 206, 207, a paper carriage escapement device is actuated. The latter consists of a feed member 208 which, by means of a stationary and a movable pawl 210 and 211, respectively, alternately engages with the teeth of a ratchet wheel 212.

If one of the type levers 200 is moved out of its position of rest shown in Fig. 5 into the printing position and back again, the feed member 208 is once swung to and fro about its axis 209, whereby the ratchet wheel 212 is released to be rotated one tooth pitch. This rotation is effected under the action of a device for drawing the carriage, for instance, a spring, not shown in the drawings, and tending to always draw the paper carriage 10 in the direction of the arrow B (Fig. 2) which ratchet wheel 212, however, by the above described escapement device 208-211, is prevented from effecting such rotation in the position of rest. The rotary movement of the ratchet wheel 212, when released by the escapement device 208-211, is transferred to the paper carriage 10 by means of a gear wheel 14 coupled to the ratchet wheel and a rack bar 13 engaging therewith and mounted on the paper carriage 10, so that during rotation of the ratchet wheel 212 for one tooth space, the paper carriage 10 performs a feed movement corresponding to the pitch of the character or letter. Such a feed movement may also be effected without printing a letter or character by actuating the so-called space bar 213, the rear end of the key lever 214 of which also acts upon the feed member 208 and allows the above described reciprocating swinging movement of the feed member 208 without simultaneously operating a type lever.

The invention is not limited to this kind of machine, and may also be used where type wheels or other carriers for characters or letters are employed. The invention may also be used if the printing movement of the carrier for the characters or letters is effected not by hand, but by some suitable power drive controlled by templets or perforated cards, or in any other suitable manner.

Finally, the invention may also be used if, during printing, the printing mechanism is moved step by step and the paper support is stationary.

In the construction according to the present invention, the rack bar 13 is not rigidly connected to the paper carriage 10, but the latter and the rack bar 13 are relatively movable in a longitudinal direction. This shifting in the longitudinal direction is permitted by the pin-and-slot guides 16, 17 shown in Figures 2 and 3 provided at both ends of the rack bar 13 and by a sleeve 19 connected to the rack bar 13, and guided upon a guide bar 18 rigidly connected to the paper car-

riage 10. The slots 16 and the guide 18, 19 extend in the direction of movement of the paper carriage. Pivoted to the sleeve 19 at 20 is one end of a connecting member 21, the other end of which is linked at 22 to the end of the vertical arm of a bell crank lever 23. The bell crank forms an actuating member for obtaining a longitudinal movement of the paper carriage 10 relatively to the rack bar 13 uniformly controlled by the escapement device 208—212. The bell crank lever 23 is pivoted at 24 to a member 25 rigidly connected to the paper carriage 10. A guide roller 26 is mounted at the end of the other arm of the bell crank lever 23, the guide roller 26 being accommodated in a rail 27 of U-shaped cross section.

This rail 27 serves for controlling the longitudinal displacement of the paper carriage 10 with regard to the rack bar 13 as effected by the actuating member 23. For this purpose the rail 27 is supported by two bolts 28 and 29 and is prevented from undesired displacement in the longitudinal direction by the bolt 33 sliding in a vertical guide 34 of a member 35 secured to the frame 9 of the machine. The bolts 28 and 29 engage a longitudinal slot 30 of the rail 27 and may be adjusted along this slot as desired. Of course, a longitudinal slot may be provided in the rail 27 for each of the bolts 28 and 29, respectively. These bolts 28 and 29 have flat heads which prevent the rail 27 from slipping off the bolts.

The bolts 28 and 29 supporting the rail 27 are connected to the depending arms 31 and 32, respectively, of the means for setting the margin. As shown in Figures 2 and 4 these depending arms 31 and 32 for setting the margin preferably are adjustable along a bar 36 provided with a scale and mounted on the frame 9 of the machine in such a manner that the depending arms may be shifted in either direction of movement of the carriage. To fix the depending arms 31 and 32 for setting the margin in various positions of adjustment upon the bar 36, locking devices 40 and 39, respectively, are provided which may be engaged with or disengaged from the serrated lower edge of the bar 36. The bolt 28 is directly fixed to the depending arms 31 for setting the margin. The bolt 29, however, is connected to a slide member 41 which is guided in a vertical direction by the fingers 42 and 43 of the depending arm 32 for setting the margin. The bolt 29, moreover, is guided in a horizontal slot 44 of a setting member which, according to the construction shown, is formed as a skeletonized plate 45. The plate 45 is mounted for vertical movement relatively to the frame 9 by pin-and-slot guides 46. Arranged on the plate 45 is a vertical rack bar 47 engaging a gear wheel 48 journalled in the frame of the machine. Preferably, the gear wheel 48 is rotated by means of a setting member from the front side of the machine. As may be seen from Fig. 5, this setting member preferably is formed as a rotatable knob 50. The gear wheel 48 is connected to the knob 50 by a shaft 49 and gear wheels 51 and 52. Both ends of the shaft 49 are provided with universal joints to obtain as good a mounting of the device in the frame 9 of the machine as possible.

Fixed to and mounted co-axially with the gear wheel 48 is a ratchet wheel 53, the number of teeth of which corresponds to that of the teeth of the gear wheel 48. A locking tooth 56 of a pawl 55 pivoted at 54 cooperates with the ratchet wheel 53. A spring 57 tends to main-

tain the locking tooth 56 in engagement with the ratchet wheel 53. The knob 50 arranged at the front of the machine, is provided with graduations, extending, for instance, on the one hand from "0" to "6" and on the other hand, from "0" to "4" to cooperate with a stationary mark M provided on the frame of the machine (see Fig. 6). The graduations correspond to the toothing of the ratchet wheel 53 and of the gear wheel 48, so that rotation of the knob 50 for one pitch corresponds to a rotation of the ratchet wheel 53 and of the gear wheel 48, as well as a lifting or lowering of the rack bar 47, for one pitch. The inclined faces of the teeth of the ratchet wheel 53 cause the locking tooth 56 of the pawl 55 to be forced out of a space between two teeth of the wheel 53 against the action of the spring 57 and, moreover, cause the pawl 55 to be rotated in an anti-clockwise direction (see Fig. 2). Owing to this rotation, a second locking tooth 58 of the pawl 55, engaging a rack bar 59, is disengaged. The rack bar 59 is fixed to the plate 45 so that upon engagement of the locking tooth 58 with such rack bar, displacement of the plate 45 in an upward direction is impossible and a displacement in a downward direction is comparatively difficult. The teeth of the rack bar 59 are so constructed that they have upwardly directed horizontal flanks and downwardly directed inclined flanks. The pawl 58, however, is provided with a horizontal lower face and an inclined upper face. If an attempt is made to move the plate 45 upwardly, the horizontal upper flank of a tooth of the rack bar is caused to bear against the horizontal lower surface of the locking tooth 58, thereby preventing an upward movement of the plate 45. Upward movement is rendered possible only if the locking tooth 58 is disengaged in the manner described above. If the plate 45 is moved downwardly, the inclined lower flank of a tooth 59 of the rack bar cooperates with the inclined upper flank of the locking tooth 58, whereby the latter, against the action of the spring 57, is forced out of the teeth of the rack bar 59 as soon as a sufficiently strong pressure is exerted upon the plate 45 from above.

This construction of the locking arrangement for the upward and downward movement, respectively, of the plate 45 has the purpose of absolutely preventing undesired movement of the adjusting device 45, 59 by the machine. The carriage feed spring, which has not been shown in the drawings, tends to move the carriage 10 and therewith also the fulcrum 24 and the fulcrum 22 of the bell crank lever 23, in the direction of the arrow B. The fulcrum 22, however, is, due to the connection 21, 20, 19, 13, 14, prevented from such a displacement by the escapement device 208—212 of the paper carriage so that a torque is formed which tends to swing the bell crank lever 23 in an anti-clockwise direction (see Fig. 2). This swinging movement of the lever 23 is prevented by the guide roller 26 engaging the upper flange of the rail 27 of U-shaped cross section. An undesired displacement of the rail 27, however, is prevented by the above mentioned locking device 58, 59. Downwardly directed pressure is not exerted upon the rail 27 and, therefore, not upon the plate 45, so that the locking or safety device needs only to prevent undesired downward movement of the plate 45 due to shocks, vibrations and the like.

The rack bar 47 is mounted on the plate 45 by means of the pin-and-slot connections 60 and

is urged downwardly by a spring 61. If the setting knob 59 is turned so that the gear wheel 48 is rotated in the direction of the arrow c (Fig. 2), then the rack bar 47 is moved upwardly along the plate 45 against the action of the spring 61, because the plate 45 is still locked by the locking pawl 55, 58. During this displacement of the rack the ratchet wheel 53 may be rotated far enough to disengage the locking tooth 58 from the rack bar 59 by swinging the pawl 55 in an anti-clockwise direction. The slots of the pin-and-slot connections 60 are so dimensioned and the spring 61 is so strong that in spite of the possibility of mutual displacement of the rack bar 47 and the plate 45, an exact and reliable movement of the plate 45 by the gear wheel 48 is ensured after the locking pawl 58, 59 is disengaged. As soon as the gear wheel 48 is rotated one tooth the locking tooth 56 of the pawl 55 engages the next tooth space of the ratchet wheel 53 which enables the pawl 55 to rock in a clockwise direction so far that the locking tooth 58 also engages the rack bar 59, thus again locking the plate 45 against displacement in a vertical direction.

By the displacement of the plate 45 in a vertical plane, the bolt 29 is raised or lowered, whereby the slide 41 is moved up and down between the arms 42 and 43 of the depending arm 32 for setting the margin, and the control rail 27 is rotated about the fulcrum formed by the bolt 28 of the depending or fulcrum arm 31 for setting the margin and adjusted in various inclined positions.

If, for instance, the control rail 27 is brought into a position inclined upwardly from the fulcrum bolt 28 to the bolt 29, then at each feed movement of the paper carriage the roller 26 is lifted for a small amount. This movement of the roller 26 causes turning of the bell crank lever 23 about the bolt 24. As, owing to the action of the feed mechanism 208, 210, 211, 212, 14 of the machine, the rack bar 13 is forced to perform feed movements of perfectly uniform length, the turning movement of the bell crank lever 23 may cause a displacement of the paper carriage 10 with regard to the rack bar 13 of the carriage only. This results in a displacement of the paper carriage 10 relatively to the rack bar 13 in the direction of the arrow d, i. e. to increase by a fixed increment, each of the feed movements of the paper carriage 10 relatively to the rack bar 13.

A position of the rail 27 inclined downwardly from the fulcrum bolt 28 to the bolt 29, therefore, effects a displacement of the paper carriage 10 with regard to the rack bar 13 in the direction of the arrow e, i. e. resulting in a shortening of the individual feed movements of the paper carriage 10 relatively to those of the rack bar 13. By adjusting the control rail 27 into various inclined positions by means of the setting knob 59 longer or shorter feed movements of the paper carriage 10 may be obtained depending on whether too short lines are to be lengthened or extended or too long lines are to be compressed or shortened.

In Fig. 1 various adjustments of the bolts 28 and 29 are indicated. In the lines 1 and 3 the bolts 28 and 29 occupy the positions indicated in the upper portion of Fig. 1 in accordance with the adjustment of the depending arms 31 and 32 for setting the margin upon the gauge lines I and II, respectively. In order to shorten the line 1, for instance, for the distance a, the con-

trol rail 27, in accordance with the above explained operation, must occupy a position inclined downwardly from the fulcrum bolt 28 to the bolt 29 which is indicated in Fig. 1 by the distance line 2. The bolt 29, therefore, must be lowered for a corresponding amount "a" from the position illustrated. In order to extend the line of text 3 about the amount "a," the control rail 27 must occupy "a" position inclined upwardly from the fulcrum bolt 28 to the bolt 29. This position is indicated by the distance line 4 in the upper portion of Fig. 1. To obtain this position, the bolt 29 must be lifted by the corresponding amount "a" from the centre position shown in the drawings. By this downwardly or upwardly inclined position of the guide rail 27 shown by the distance lines 2 and 4, respectively, the length of each normal letter spacing step to be transmitted from the carriage feed rack 13 to the paper carriage 10, is increased or decreased by an equal amount from the beginning of the line of text, indicated by the gauge line I, to the end of such line, indicated by the gauge line II. The amount of the additional movement depends on the degree of inclination of the control rail 27.

Preferably, the arms of the actuating lever 23, transferring the control movement from the rail 27 to the paper carriage, are of equal length so that the amount of the additional displacement of the paper carriage corresponds to the amount of upward inclination of the rail 27 over the portion of the longitudinal movement of the paper carriage in consideration, that is, in accordance with the sine of the angle. In this manner the amount by which the control rail 27 is to be lifted or lowered, respectively, may be maintained exactly equal to the amount by which the lines of text are to be lengthened or extended, or shortened, respectively.

From a consideration of Fig. 1 it is to be seen that for compensating the longer lines 5 and 7 in which the depending arms 31 and 32 for setting the margin are adjusted along the supporting bar 36 according to the gauge lines III and IV, respectively, and in which the bolts 28 and 29 occupy the positions 28' and 29', respectively, a smaller inclination of the control rail 27 results if the bolt 29 is adjusted upwardly or downwardly, respectively, by the same amount "a." The corresponding downward and upward inclination, respectively, of the control rail is indicated in Fig. 1 by the disk lines 6 and 8, respectively. It may, therefore, clearly be seen that with longer lines of text a smaller additional movement of the paper carriage at each feed movement is required to effect compensation of the same distance "a".

For lifting or lowering the control rail 27 from the horizontal position shown in Fig. 1 by the line 0, respectively, the bolt 29 is lifted or lowered, respectively, in the manner described, by the plate 45. This is effected by actuating the setting knob 59. If, in the individual lines of text amounts differing from each other are to be compensated, i. e. if, for instance, the first line is to be shortened for two character or letter movements, the second line is to be shortened for three character or letter movements, the third line is to be extended or lengthened for four character or letter movements and so on, then, of course, in each individual line a corresponding lifting or lowering, respectively, of the bolt 29 and therewith of the control rail

27 is to be effected by a corresponding adjustment of the setting knob 50.

The different adjustments of the rail 27 in the inclined positions in accordance with various lengths of lines of text as explained in connection with, Fig. 1 automatically results from the adjustment of the bolts 28 and 29, supporting the rail 27, in the slot 30 during adjustment of the depending arms 31, 32 for setting the margin. By the adjustment of the depending arm 31 for setting the margin and, therefore, by the adjustment of the bolt 28, the fulcrum of the guide rail 27 is altered, whereas by the adjustment of the depending arm 32 for setting the margin and, therefore, by the adjustment of the bolt 29, the position of the point of application of the force for lifting or lowering the rail 27 is altered. The bolts 28 and 29 are so positioned with regard to the depending arms 31 and 32, respectively, for setting the margin that the axial center of each of these bolts exactly corresponds with the beginning and the end of the line, respectively, i.e. exactly corresponds to the position of the vertical gauge lines I, III and II, IV, respectively, in Fig. 1.

The graduation upon the setting knob 50 is so chosen that with the adjustment upon the graduation line 0, shown in Fig. 6, the guide rail 27 occupies the horizontal position according to Fig. 2. Turning the setting knob 50 from the zero position into the position "+1" effects rotation of the gear wheel 48 in the direction of the arrow c for one tooth, whereby the plate 45 and the bolt 29 also are lifted by this angular amount and the rail 27 is adjusted upwardly by the amount mentioned, from the bolt 28. This inclination of the rail causes a lengthening of a line for one character or letter. Therefore, with adjustments of the setting knob 50 to the graduation lines +1, +2, +3, +4, +5, +6 lengthenings of the lines to be justified for amounts of 1, 2, 3, 4, 5, or 6 characters or letters are effected. By adjustment of the setting knob 50 upon the graduation lines -1, -2, -3, -4, however, shortenings of the lines for 1, 2, 3, or 4 characters or letters are obtained. Of course, another distribution of the graduations on both sides of the graduation line "0" may be provided depending upon the desired range of justification.

For designating the settings, arrows or words may be provided upon the knob 50 instead of the signs "+" and "-".

The arrangement is such that in the position in which the paper carriage at the beginning of a line, strikes against a corresponding stop for the depending arm 31 for setting the margin, the guide roller 26 of the actuating lever 23 comes into the range of the bolt 28. Of special advantage is an arrangement according to which, in the above mentioned starting position of the paper carriage, the bolt 28 and the roller 26 are so positioned with regard to each other as to occupy one and the same vertical plane that is, the roller 26 and the bolt 28 lie in axial alinement. The importance of this arrangement will be explained in detail when the mode of operation of the device according to the invention is described.

At the first printing of a document, the setting knob is adjusted to the zero position, i. e. the control rail 27 is brought into a horizontal position (Fig. 2). The paper carriage 10 and the rack bar 13 are permanently maintained in the same relative position during operation of the machine, because the roller 26 and its bell-crank 23 are not displaced by the rail 27 during the travel of the paper carriage. With this adjust-

ment the machine operates in exactly the same manner as if the carriage 10 and the rack bar 13 were rigidly connected to each other. At the end of each line of the first printing, a line scale 70 on the machine frame and a pointer 71 on the paper carriage 10 (Fig. 7) indicate the amount by which the printed line is shorter or longer than the desired length of line. If, after printing the last character or letter of a line which, for instance, is to be justified for 75 character or letter spaces, the pointer 71 of the paper carriage 10 points to the graduation line 73 of the scale, then this line is to be lengthened or extended by the amount of two characters or letters to obtain the required justification. In this case the number +2 may be printed adjacent and beyond the end of the line. Inversely, a line of the first printing which, for instance, is too long by the amount of three characters or letters may be provided with the mark -3. This means that, in order to effect the desired justification of the line this line is to be shortened by the amount of three characters or letters.

When the first printing is finished then at the second justified printing, the setting knob 50 is, before starting the printing of each line, brought into the position which is indicated by the mark printed at the end of the corresponding line of the first printing, whereby the above described setting operations are carried out and shortening or lengthening of the line by the desired amount is rendered possible. During this adjustment at the start of a line, the paper carriage occupies the end position determined by the position of the stationary stop arm 31 for setting the margin (Fig. 2). As mentioned already, the roller 26 of the actuating lever 23 now occupies such a position with regard to the fulcrum 23 of the control rail 27 that the roller 26 and the bolt 28 have a common vertical plane of symmetry, that is, in axial alinement. In this position of the roller 26 relatively to the bolt 28 the roller and its bell crank 23 are not influenced by the swinging of the control rail 27. To better comprehend the effect of this adjustment, suppose that, in the starting position of the paper carriage the roller 26 should occupy a position somewhat to the left or to the right of the bolt 28 (Fig. 2), then on swinging the rail during adjustment to the amounts of justification at the beginning of each line, the roller 26 would be lifted or lowered and thereby the paper carriage 10 would be displaced with regard to the rack bar 13. Since generally, when making a justified printing, an adjustment of the guide rail 27 is required for each line, the mentioned resulting displacements of the paper carriage 10 with regard to the rack bar 13 at the beginning of the line also would be different for each line, so that a uniform left hand margin of the document could not be obtained.

To facilitate reading off the justification amounts for each individual line, the device shown in Fig. 7 may, for instance, be used. Along the line scale 70 of the machine a short scale 72 may be shifted and fixed in any desired position of adjustment with regard to the scale 70. The scale 72 carries a small pointer 73 bearing the mark "0." At one side of this mark a graduation from "1" to "6" with the sign "+" and on the other side, a graduation from "1" to "4" with the sign "-" is provided. The graduation lines of the short scale 72 are spaced from each other the same distance as the graduation lines of the scale 70. Before starting the first,

i. e. the non-justified printing, the pointer 73 of the short scale 72 is adjusted to the graduation line of the line scale 70 which corresponds to the desired justified end of the line. In Fig. 7, this is the graduation line "75" of the scale 70. If the carriage pointer 71, after printing the last character or letter of a line, stops in the position shown in Fig. 7, then it points to the graduation line +2 of the short scale 72. This means that the line just printed is shorter by the amount of two characters or letters than the desired length of the justified line and, therefore, is to be lengthened by the amount of two characters or letters when making the second justified printing. The provision of the scale 72, therefore, renders superfluous the counting or calculating of the amounts of justification necessary for each printed line and assists in obviating mistakes.

As the exact and reliable ascertaining of the amounts of justification during the first printing is of special importance for obtaining the justified second printing, a particular advantage is to be considered in a further improvement of the device according to the invention, by means of which these amounts of justification are automatically recorded by the machine at the end of the individual lines of the first printing. This record, therefore, is effected independently of the attention and the exact operation of the operator. The additional improvement consists in the device shown in Figs. 9, 10, 11 and 12.

Adjacent the conventional type guide 80 a series of resilient tongues 81 is provided on the frame 9 of the machine, the upper ends of which, facing platen 82, carry numeral or digit types 83. In the construction shown, the first four types from the left (Fig. 9) and from the right (Fig. 12), respectively, are provided with inclined numeral types 4, 3, 2, 1. Fig. 12 illustrates the arrangement of the numeral types 83 on the tongues 81 in an elevation shown in the direction of the arrow D in Fig. 11. The fifth tongue 81 from the left (Fig. 9) and from the right (Fig. 12), respectively, carries the cipher "0" and the following types to the left, Fig. 12, carry vertically arranged numerals "1" to "6." By means of a sleeve 89, a cam 88 is mounted to be slid along the paper holding rail 84, which is swingably mounted in the paper carriage frame by means of arms 85, 86 and a sleeve 87. The sleeve 89 carries a resilient indexing tongue 90 which presses against the upper surface of the paper holding rail 84 and holds the sleeve 89 and the cam 88 upon the paper holding bar 84 in any of its adjusted positions. The end of the resilient indexing tongue 90, Fig. 10, also serves as a pointer cooperating with the graduation provided upon the paper holding bar 84. This bar 84 is journaled at 91 and 92 in swinging arms 85 and 86. One end of the bar 84 extending beyond the swinging arm 85 carries a crank 93 provided with a crank pin 94 with which cooperates an arm 95 of the feeding lever 96 of the machine. Adjacent the crank 93 a spring 97 is provided which tends to rotate the paper holding bar 84 into the position shown in Figs. 9, 10 and 11. In this position, the cam 88 occupies relatively to the platen 82, the position shown in full lines in Fig. 11. Further rotation of the cam 88 towards the platen 82 may be prevented by a stop limiting the rotation of the bar 84. If the line feeding lever 96 is actuated, the extension 95 strikes against the crank pin 94 and rotates the crank 93 and the paper holding bar 84 against the action of the spring 97 to swing the cam 88 in the direction of the

arrow 2 (Fig. 11). When occupying a position in the range of any of the resilient type-carrying tongues 81, the end 98 of the cam 88 presses against the upper end of one of these type-carrying tongues and bends its free upper end away from the platen until the end 98 of the cam 88 slides off the end of the flexed resilient, type-carrying tongue 81, whereupon the latter springs back and strikes its type 83 against the platen 82. All the resilient type-carrying tongues 81 are connected with a rail 99 which, by means of arms 100 and 101, is swingably mounted at 102 and 103 on the machine frame 9 and is held in a position in contact with the backs of the resilient type-carrying tongues by means of a spring, not shown in the drawings. The arm 100 of the rail 99 has an extension 104 which engages a member 106 of the ribbon fork 105. If, by flexing one of the resilient type-carrying tongues 81, the rail 99 is swung in a direction away from the platen, then the ribbon fork 105 is lifted by the connecting members 103, 104, 106 and the ribbon 107 is lifted so far as to occupy a position between the types 83 and the platen 82. If, now, the corresponding resilient type bar 84 is released by the end of the cam 88 and springs against the platen 82, printing upon the paper surrounding the platen is effected by means of the ribbon 107 at a point spaced to the right of, and in line with the printed line of text.

Of course, instead of the above described device for lifting the ribbon any other inking mechanism for the types 83 may be used, and which may be brought to action in the corresponding manner.

The device shown in Figs. 9, 10, 11 and 12 operates in the following manner:

On the first printing of a document to be justified or equalized, the end of the indexing tongue 90 is adjusted by shifting the sleeve 89 along the graduated paper holding rail 84 to a position corresponding to the desired end of the line, for instance, to the graduation line 32 in Fig. 12. Assume that the position of the resilient type-carrying tongues 81 with regard to the printing point of the types and the position of the indexing tongue 90 with regard to the tripping cam 88 are so chosen that the cam 88, after the printing of the last character or letter of a line of the first printing which, by chance, has the desired length, comes to rest just in front of the resilient type-carrying tongue 81 carrying the type 0. To be able to print the next line of the first printing, the paper carriage must be shifted back to the starting position in the direction of the arrow A (Figs. 9 and 10). This is effected in the usual manner by means of the feeding or line-spacing lever 96. The movement of the carriage and the feeding of the lines are effected by a single operation. The arrangement is such that, upon operation of the line spacing lever 96, its arm 95 first actuates the crank pin 94 to partially rotate the paper holding rail 84 together with the tripping cam 88 in the manner described above, whereby the corresponding type-carrying tongue 81 prints its type 83, in the example given, a "0" to the right of, and spaced apart from the right hand end of the line. The zero at the end of the line then indicates that in making the second printing, the setting knob 59 (Figs. 5 and 6) is to be adjusted to the graduation line "0" for this line. After printing of the type 83, the line feeding is effected by a further swinging of the lever 96, whereupon or simultaneously with the feeding of the line the paper carriage is shifted in the di-

rection of the arrow A (Figs. 9 and 10). After release of the feeding lever 96, the latter returns to its starting position shown in Fig. 10 and the paper holding rail 84 is rotated backwardly by the spring 97 so that the tripping cam is returned from its swung out position 88', shown in dotted lines in Fig. 11, into the position of rest 88. As the next line of the trial or first printing is typed, the paper carriage is moved towards the left, and the tripping cam, at the end of the line, again occupies a position between the platen 82 and the type-carrying tongues 81. Depending on whether the lines of the first printing are, for instance, shorter by the amount of two characters or letters, or larger by the amount of four characters or letters than the desired length of justification, the tripping cam 88 stops at the end of this line in front of the resilient torque 81 carrying the even type numeral 2, or the type-carrying tongue bearing the rearwardly inclined type numeral 4 (Fig. 12), and in the manner described above, prints this numeral incident to the operation of feeding the line. In this manner the automatic printing of the amounts of justification is effected without the operator being compelled to count the required increments of justification, to calculate them, or to read them off a scale and write them down.

Of course, instead of arranging the numeral type at the right and left of the "0" position (Fig. 12) in various inclined positions, other discriminating marks also may be introduced to indicate to the operator the proper adjustment of the setting knob 50 for each line of the second printing.

When making the second justified printing no characters should be printed at the end of the lines, as that would mar the appearance of the printing. Moreover, due to the uniform length of all lines the same character or numeral would be printed which, in the present example, would be "0" because of the adjustment of the indexing tongue 99 on the rail 84 to "0". The tripping cam 88, therefore, preferably may be rendered inoperative. This may be effected, either by shifting the sleeve 89 to a point on the paper holding rail 84 which, at the end of the line, is out of the range of the resilient type-carrying tongues 81, or by means of a device known per se, the paper holding rail 84 may be lifted from the platen 82 to shift the crank pin 94 out of the range of the arm 95, so that when feeding the lines no rotation of the paper holding rail 84 and, therefore, of the tripping cam 88 is effected.

Such a lifting device is shown in Figs. 9 and 10. The swinging arm 86 carries a member 111 which, by means of a handle 110, may be swung about an axis arranged in parallel to the paper holding rail 84. A cam surface 112 on the member 111 bears at 113 upon the frame 10 of the paper carriage. On turning the member 111 in one direction the cam surface 112 causes swinging of the arm 86 to swing the paper holding rail 84 away from the platen 82. Swinging of the member 111 in the other direction restores the paper holding rail 84 into the position shown in Figs. 9, 10 and 11 opposite the platen 82. To ensure that in both positions of the paper holding rail 84, the rollers 120 pressing the paper against the platen bear against the sheet to be printed, the paper holding rollers 120 are, as shown in Fig. 9, journaled in arms 119 of guide sleeves 121 to resiliently bear against the platen 82. Said guide sleeves 121 are adapted to be shifted along the rail 84 and remain in any desired position of adjustment.

Without departing from the spirit of the invention it is, of course, possible to make a number of modifications different from the example described above. So, for instance, the device for lifting and lowering the plate 45, instead of being operated by means of a gear wheel and a rack bar, as shown in Fig. 2, may be operated by means of curved guide members or eccentric devices shown in Fig. 8. Instead of the gear wheel 43, the curved disc 130 (Fig. 8) is used which is fixed to the ratchet wheel 53 and rotated with the latter. The curved disc 130 has an eccentric guide slot 131 into which engages a follower 132 provided on the plate 45. The follower 132 used in this modification instead of the rack bar 47 according to Fig. 2, may, like the latter, be shifted in a vertical direction for a small amount. The follower 132 is guided by elongated holes 133 and is drawn into its lower position by a spring 134. The other constructions and the operation of the device according to Fig. 8 are the same as described with reference to Fig. 2.

In the machine according to Figs. 2 and 5, the arrangement for setting the margin is provided at the rear side of the machine which results in a particularly simple connection to the guide rail 27. The device according to the invention may also be used in connection with machines in which the devices for setting the margin are not provided at the rear side of the machine. For such machines, the arrangement shown in Figs. 13, 14 and 15 allows a corresponding registering adjustment of the devices for setting the margin arranged at the front side of the machine and of the bolts 23 and 29 holding the control rail 27.

The two stops 140 and 141 for setting the margin are, in this case, arranged at the front of the frame 9 of the machine upon a rack bar 142 and may be longitudinally displaced and fixed in any position of adjustment. Each of the two stops 140 and 141 for setting the margin has a pointer 144 and 143, respectively. These pointers cooperate with a line scale 145 fixed to the frame 9 of the machine above the rack bar 142. The stop 140 for setting the margin is linked by means of a connecting member 146 to an arm 147 fixed upon a shaft 148. The latter is journalled in the frame 9 of the machine and at the rear of the machine, carries an arm 149 which also is fixed upon the shaft and is linked by means of a connecting member 150 to a slide member 151 (Fig. 14). The slide member 151 is displaceably arranged along the horizontal slot 144 of the plate 45 and carries the bolt 29 supporting one end of the control rail 27. Depending upon the position of the stop 140 for setting the margin, the bolt 29 occupies a corresponding position in the slot 33 of the control rail 27. At the rear of the machine the slide member 152 is associated with, for adjustment by the stop 141 for setting the margin. The slide member 152 is displaceably arranged in a horizontal direction along the slot 153 of the plate 154 fixed to the frame 9 of the machine and carries the fulcrum bolt 23 supporting the other end of the control rail 27. The rail 27 carries, in a manner similar to that shown in Fig. 2, a bolt 33 which is guided in a slot 34 of the stationary plate 154 in a vertical direction and prevents undesired displacement of the rail 27 in the longitudinal direction. The slide member 152 carries a pawl 155 which is pivoted at 156 and is acted upon by a spring 157. By the action of this spring a tooth 158 of the pawl 155 engages a rack bar 159 which is swingably mounted at 160 on the stationary plate 154. The

end 161 of the rack bar is provided with two steps and is supported by the end 162 of a lever 163 pivoted at 164 to the frame 9 of the machine. A spring 165 tends to rotate the lever 163 in an anti-clockwise direction (Fig. 15) to bring the end 162 into the position in which it holds the rack bar 159 in the position shown in Fig. 13 against the action of the spring 165'. If the lever 163 is rotated in a clockwise direction until it strikes against the abutment 174 of the frame 9 of the machine, the end 162 of the lever disengages from the lowermost step of the end 161 of the rack bar, whereupon the rack bar 159, under the influence of the spring 165', is swung downwardly until the second step of the end 161 of the rack bar bears against the end 162 of the lever, thus disengaging the rack bar 159 and the tooth 158 of the pawl, as the pawl 155, due to the action of the stop 166, cannot be swung further downwardly, as shown in Fig. 13, and, therefore, is not capable of following the downward movement of the rack bar 159. The slide member 152 is urged towards the right (Figs. 13 and 15) by a spring 167, one end of which is connected to an arm 168 of the slide member 152, whereas the other end is fixed to the frame 9 of the machine. The engagement of the tooth 158 of the pawl 155 with the rack bar 159 prevents the movement of the slide member 152 towards the right (Fig. 13) under the action of the spring 167. When, as described above, the lever 163 is rocked counter-clockwise, the rack bar 159 is swung downwardly, releasing the locking mechanism mentioned above and the slide member 152 is moved along the guide slot 153 under the action of the spring 167, thus shifting the fulcrum bolt 23 along the slot 30 of the control rail 27. To bring the slide member 152, and thereby the bolt 23, always into the position of adjustment which corresponds to the adjustment of the stop 141 for setting the margin, a stop bolt 169 is provided on the arm of the actuating lever 23 carrying the guide roller 26, which stop bolt 169 cooperates with a catch 170 pivoted at 171 to the slide member 152. The arm 172 of the catch extends into the path of the stop bolt 169 and its other offset arm 173 engages beneath the rack bar 159. As clearly shown in Fig. 2, the actuating lever 23 is swingably mounted at 24 on a member 25 rigidly connected to the frame 9 of the paper carriage. If, during return travel of the carriage, the paper carriage and therewith the actuating lever 23 are moved in the direction of the arrow A then the stop bolt 169 strikes against the end 172 of the catch 170 and on its further movement, drives the slide member 152 to shift the pawl 155 relatively to the rack bar 159. Finally the paper carriage strikes against the stop 141 for setting the margin to arrest the slide member 152. The stop 141 for setting the margin and the slide member 152, particularly the bolt 23, then occupy corresponding positions. If, on adjusting for a new line, the slide member 152 occupies a position at the left of the stop 141 for setting the margin (Figs. 13, 15), then the paper carriage, on its return travel in the direction of the arrow A, is arrested by the stop 141 for setting the margin before the stop bolt 169 reaches the catch 172, 170 of the slide member 152. Due to the paper carriage striking the stop 141 for setting the margin in the direction of the arrow A, the rack bar 142, which may resiliently be shifted slightly in the longitudinal direction, is displaced in the direction of the arrow A. During this displacement, a

projection 175 of the rack bar 142 (Fig. 15) contacts the forward end 176 of a restoring lever 178 mounted at 177 on the frame 9 of the machine and rotates the lever 178 in an anti-clockwise direction. The rear end 179 of the lever 178, carrying a projection 180, is thus shifted towards the right and causes its projection 180 to strike the end 161 of the lever 163. Against the action of the spring 165, the lever 163 is hereby rotated in a clockwise direction, the rotation being limited by the stop 174 as mentioned already above. During this rotation, the end 162 of the lever 163 is withdrawn from beneath the end 161 of the rack bar 159, whereupon the latter swings downwardly and the tooth 158 of the pawl disengages from the rack bar 159. The slide member 152 now moves under the action of the spring 167 until the end 172 of the catch 170 strikes against the stop bolt 169. Hereby the lever 178 is rotated in an anti-clockwise direction (Fig. 13) and the opposite, offset arm 173 presses from below against the rack bar 159 to rock the rack bar upwardly against the action of the spring 165'. After the arrest of the carriage by the stop 141 for setting the margin, the lever 163 is released by the projection 180, the spring 165 rotates said lever in such a manner that its end 162 engages again below the lowermost step of the end 161 of the lifted rack bar 159 to maintain the rack bar in the position shown in Fig. 13. The tooth 158 then again engages the rack bar 159 so that further movement of the slide member 152 by the spring 167 is prevented. The slide member 152, and therewith the fulcrum bolt 23 supporting the rail 27 is either shifted by the paper carriage into the position corresponding to the adjustment of the stop 141 for setting the margin, or said member, under the action of the spring 167, automatically springs into the desired correct position. The operator only needs to adjust the stop 141 for setting the margin and to return the paper carriage in the direction of the arrow A into its starting position.

To prevent idle running and vibrations, the paper carriage 10 and the rack bar 13 may be connected by a special spring 198, Figs. 2 and 5, in addition to the connection shown in Figs. 2 and 3 consisting of the members 26, 23, 21, 19. One end of the spring 198 may be fixed to a stud 192 on the sleeve 19 adjacent the sleeve 19 and the other end to a stud 191 on the paper carriage 10. Owing to this arrangement, the spring 198 effects a dampening action between the relatively movable members 13 and 10.

As the device according to the invention, permits the adjustment of a writing machine to longer or shorter feed movements, the invention may also serve the purpose of easily and quickly adjusting the machine to various kinds of writing. If, for instance, a set of types is to be mounted in the machine which effects printing of broader characters and letters and, therefore, requires correspondingly longer letter spacing feed movements of the paper carriage than the set of types hitherto used in the machine, then by adjusting the setting knob 50 (Figs. 5 and 6) in the direction of the arrow designated with "+" and by bringing the rail 27 into an inclined position in the manner described above, a displacement of the paper carriage 10 relatively to the rack bar 13 may be effected which corresponds to the desired lengthening of the feed movements of the machine. In a similar manner it is possible to easily and quickly change from a feed

movement adapted for printing larger characters to one adapted for printing smaller characters. In order to be able to obtain justification of the lines with any desired characters or letters, it is advisable to construct the device for adjusting the setting members 28, 29 carrying the control rail 27 in such a manner as to allow adjustment from the normal pitch, to the pitch of the character. For instance, the device shown in Fig. 8 for adjusting the setting member 29 in a vertical direction by means of a cam is capable of being adapted to various large adjustments.

Another modification of the subject matter of the invention, according to which, the adjustment of the guide rail 301 is effected by setting curves is shown in Figs. 16-19. The device has been shown in connection with a simple typewriting machine of usual construction such as has been generally explained already at the beginning of the specification. At this point, therefore, it is deemed sufficient to briefly refer to the parts already described. 300 is the platen rotatably mounted in the paper carriage 320 which is guided upon rails 321 mounted upon the machine frame 322. By depressing the character or letter keys 323, Fig. 19, or the spacing bar 328, the escapement device of the paper carriage, including the stationary and movable pawls 324 and 325, and the ratchet wheel 326, are moved under the action of the spring for drawing the carriage which is not shown in the drawings. This spring is connected to the paper carriage 320 and tends to shift the paper carriage and the rack bar 304 in the direction of the arrow B which carriage shifting in the position of rest of the device, is prevented by the escapement device 324-326 through the intermediary of the gear wheel 327. The rack bar 304 and the paper carriage 320 are relatively movably arranged in the longitudinal direction. This shifting in the longitudinal direction is ensured by the pin-and-slot guides 306, 307 at both ends of the rack bar 304 and by a pin-and-slot guide 328, 329, the guide pin 329 and the guide slot 328 of which are mounted on the paper carriage 320 and a member 330, respectively, which latter is rigidly connected to the rack bar 304. The slots 306, 307 and 328 extend in the direction of the longitudinal movement of the paper carriage. Between the paper carriage 320 and the member 330 fixed to the rack bar 304, a spring 331 is arranged, as shown in Fig. 16, which has a shock deadening action upon the movements of the relatively movable members 320 and 304. The carriage feed spring acting upon the carriage and not shown in the drawings, tends to always draw the paper carriage 320 in the direction of the arrow B. The rack bar 304 and the member 330 connected thereto, as well as the roller 332, are prevented from moving in the direction of the arrow B by the action of the escapement device 324-326 controlling the movements of the paper carriage. Under the action of the spring moving the carriage, the setting cam 305 connected to the paper carriage 320 bears against the roller 332 connected to the rack bar 304. By rotating the setting cam 305 the paper carriage 320 may be shifted with regard to the rack bar 304, either in the direction of the arrow B, or in the direction opposite thereto, depending on the direction of rotation of the setting cam 305. The rotation of the setting cam 305 is effected by shifting a rack bar 315 engaging a gear wheel 316 rigidly connected to the setting cam 305. By means of screws 333, for instance, the rack bar 315 is fixed to a mem-

ber 334 which is guided by an elongated slot 335 on the bolt 329 and by another slot 335' on the bolt 336. The latter is fixed to a support 338 which, for instance by screws 337, is rigidly connected to the paper carriage 320. Linked to the member 334 at 343 is a connecting member 344, the other end of which is linked at 345 to the end of a lever 341. By means of a stub shaft 339 journaled in the frame 320 of the paper carriage, the lever 341 is connected to another lever 303, the end of which carries a freely rotatable guide roller 302. The lever 303 together with the guide roller 302 forms an actuating member for obtaining a longitudinal movement of the paper carriage 320 relatively to the rack bar 304, uniformly controlled by the escapement device 324-326. The guide roller 302 runs upon a rail 301 serving to control the longitudinal movement of the paper carriage 320 relatively to the rack bar 304, which is effected by the actuating member 302, 303. To this purpose, the rail 301 may be adjusted to various inclined positions and, therefore, one end of the bar 301 is swingably mounted at 350 on the frame of the machine, whereas the other end is guided by means of a bolt 351 engaging a slot provided in the frame 322 of the machine. The adjustment of the guide rail 301 to different inclined positions is effected by rotating a setting knob 313 provided at the front of the machine, as shown in Fig. 18 which, by way of a shaft 359 journaled in the machine frame 322, rotates a setting eccentric 309. The latter acts upon a lever 308 mounted at 355 on the machine frame 322 and carrying a roller 357 bearing upon the recessed edge or periphery of the setting eccentric 309. The lever 308 has a guide slot 356 into which extends the bolt 354 of a setting member 319 which is hinged at 353 to the guide rail 301. A spring 358 connected to the lever 308 draws downwardly said lever as well as the setting member 319 and the guide rail 301. At the edge of the setting eccentric 309 notches are provided into which drops the roller 357 of the lever 308 under the action of the spring 358. The distribution of the notches or seats around the periphery of the setting eccentric 309 corresponds to the graduations of a scale 314 with which cooperates a pointer 360 fixed to the knob 313. In accordance with the graduation of the scale 314, various inclined positions of the guide rail 301 may be obtained by rotating the knob 313. The adjustment of the guide rail 301 into any of its inclined positions is, moreover, influenced by another setting knob 312 provided at the front of the machine. Preferably the setting knob 312 is coaxially mounted with the knob 313 and acts by way of a hollow shaft 361 upon a setting cam 310 which, in the example shown in the drawings, is arranged co-axial with and adjacent the setting eccentric 309. Manual rotation of the setting knob 313 and its setting cam 310 will rock to various angular positions a bell crank lever 311, mounted at 362 on the machine frame and actuated by the spring 358 tending always to rotate this bell crank lever in an anti-clockwise direction. That arm of the bell crank lever 311 cooperating with the setting cam 310 carries a preferably freely rotatable roller 363. The end of the other arm of the bell crank lever 311 is linked to the setting member 319 by a connecting member 364. If the bell crank lever 311 is rotated, the setting member 319, due to this linked connection, is rocked about the point 353 so that the bolt 354 of the setting member 319 is shifted in one direction or the other along

the guide slot 356 of the lever 308. Owing to this movement of the bolt 354, the throw of the lever arm 308 is varied, because the length of travel of which always corresponds to the distance of the pivot points 355, 354 from each other. Thereby the velocity ratio also is altered by which the up-and-downward movement of the roller 357 obtained by rotating the setting eccentric 309, is transferred to the guide rail 301. This second setting is effected in the construction shown, by way of example in the drawings, by means of a graduated disc 317 connected to the setting knob 312 which, during rotation of the latter, is moved along a stationary pointer 365, as may be seen from Figs. 18 and 19.

Under the action of the carriage spring, the roller 332 and the setting cam 305 are forced against each other, which tends to always rotate the cam in a clockwise direction (Fig. 16). As a result, the member 334, by means of the gear wheel 316 and the rack bar 315, is drawn towards the right and turns the lever 341, the stub-shaft 339 and the actuating member 303, 302 in a clockwise direction (Fig. 17). The roller 302, therefore, is pressed against the guide rail 301. The actuating member 303, 302 and, therefore, the paper carriage 320 may only be shifted with regard to the rack bar 304 if the guide rail is not in a horizontal, but in an inclined position.

As mentioned above, to obtain the justified printing a first printing of the corresponding text is to be made in which the guide rail 301 is horizontally adjusted and the typewriting machine operates in the manner of an ordinary typewriting machine. As also explained already, the lengths of justification to be considered for the individual lines of the second printing are ascertained by means of the first printing. The device is always adjusted to these lengths of justification before printing a line of the second printing. This adjustment is effected by means of the setting knob 313, the pointer 360 and the scale 314. The adjustment by means of the setting knob 313 alone, however, is not sufficient to effect the desired justification of the lines in each case. If for instance the pointer 360 is adjusted upon the number "3" of the scale 314, then this means that a lengthening by the amount of three ordinary character spaces is to be effected for the corresponding line. A line of sixty ordinary character spaces which is to be lengthened by the amount of three such spaces evidently requires a greater inclined position of the guide rail than a line with ninety ordinary character spaces which is to be lengthened by the same amount, because in the first case, the length of justification is to be distributed over sixty character spaces, whereas in the second case, over ninety. The adjustment of the guide rail 301 by the actuation of the setting knob 313, therefore, requires an adaptation to the length of line in question which is effected by means of the knob 312, the scale dial 317 and the pointer 365. The scale 317 has a graduation corresponding to the various lengths of lines. In Fig. 19, for instance, a setting of a line of eighty ordinary character spaces is shown. By turning the knob 312, the setting cam 310 is actuated and effects the above explained alteration of the angular displacement of the lever 308. The two individual adjustments of the setting eccentric 309 and the setting cam 310 are combined by special leverages 308, 311, 364, 319 to a total adjustment which is imparted to the control member, i. e. the rail 301, by means of the adjusting member 319. This con-

trol member to which an actuating member 303, 302 effecting the additional movement of the paper carrier 300 is connected, therefore, may be adjusted, on the one hand, in accordance with various differences in the lengths of the lines, and on the other hand, in accordance with the length of the line.

What I claim is:

1. A device adapted to be used in connection with typewriting machines, including a paper carriage, and letter feed means therefor, means for varying the length of the letter feed movements of the carriage to justify the lines of writing to a desired uniform length, an actuating member to effect an additional movement of the paper carriage, control member connected to said actuating member, and means to adjust said control member, on the one hand, in accordance with various differences in the lengths of the lines, and on the other hand, in accordance with the length of a line, and means to operate said control member.
2. In a writing machine, the combination with keys; a traveling carriage; an escapement rack; and means to release the rack for successive equal increments of movement in letter-spacing direction upon operation of the keys; of a justifying mechanism to increase or decrease the length of such equal increments to justify the lines of writing to a desired uniform length, including means to support the escapement rack on the carriage for relative longitudinal movement; a shiftable actuating member connected with the escapement rack and the carriage, respectively; an adjustable control member with which the actuating member engages, to shift the actuating member to positions wherein it transmits to the carriage, increments of movement of greater or lesser length than those of the escapement rack; and means to adjust the control member according to the various differences in the lengths of the written lines over or under the desired uniform length of line, including a slide member connected with the control member; and means to manually adjust the slide member.
3. In a writing machine, the combination with keys; a traveling carriage; an escapement rack; and means to release the rack for successive equal increments of movement in letter-spacing direction upon operation of the keys; of a justifying mechanism to increase or decrease the length of such equal increments to justify the lines of writing to a desired uniform length, including means to support the escapement rack on the carriage for relative longitudinal movement; a shiftable actuating member connected with the escapement rack and the carriage, respectively; margin-setting stops; an adjustable control member with which the actuating member engages, to shift the actuating member to position wherein it transmits to the carriage increments of movement of greater or lesser horizontal extent than those of the escapement rack, said control member being fulcrumed on one of said margin-setting stops defining one end of the carriage travel; and means to variously position the control member to compensate for differences in the lengths of the lines, and also according to the desired uniform length of line, including a connection between the control member and the remaining margin-setting stop for defining the opposite end of the carriage travel, said connection being adjustable longitudinally of the control member towards or from the fulcrum

of the control member, incident to adjustment of its margin stop, and also being adjustable for vertical movement relatively to its margin stop to position the control member at various angles above or below the horizontal; and manually operable means to adjust said connection and the control member vertically relatively to its margin stop, whereby the control member is rocked on its fulcrum.

4. In a writing machine, the combination with keys; a traveling carriage, an escapement rack; and means to release the rack for successive equal increments of movement in letter-spacing direction upon operation of the keys; of a justifying mechanism to increase or decrease the length of such equal increments to justify the lines of writing to a desired uniform length, including means to support the escapement rack on the carriage for relative longitudinal movement; a shiftable actuating member connected with the escapement rack and the carriage, respectively; margin-setting stops; an adjustable control member engaged by the actuating member, and fulcrumed on one of said margin-setting stops; and means to variously position the control member to compensate for differences in the lengths of the lines over or under the desired uniform length of line, and also according to the uniform length of line desired, including a slideable connection between the control member, the remaining margin-setting stops, and the actuating member, whereby adjustment of said remaining margin-setting stop will shift the connection toward or from the fulcrum of the control member; and manually operable means to shift the slideable connection and the control member substantially vertically, the combined adjustments operating to vary the ultimate length of letter-spacing movement imparted to the carriage from the letter-spacing rack.

5. A device adapted to be used in connection with typewriting machines, having a carriage, and letter-feed mechanism for the carriage; means to alter the length of the feed movements of the carriage to justify the lines of writing to a desired uniform length; an actuating member to effect an additional movement of the carriage; a control member connected to said actuating member; and means to adjust said control member in accordance with various differences in the lengths of the lines, and also, according to the desired length of uniform lines; margin-setting stops; said control member being fulcrumed on one of said margin-setting stops, and connected with the other of said margin-setting stops; a connection included in said devices for setting the margin being shifted by said paper carriage and the intermediary of the stops; and a locking mechanism to prevent displacement in each adjusted position.

6. A device adapted to be used in connection with typewriting machines, including a paper carriage; and letter-feed mechanism for the carriage; means to alter the length of the feed movements of the carriage to justify the lines of writing to a desired uniform length; an ac-

tuating member to effect an additional movement of the paper carriage; a control member connected to said actuating member; margin-setting stops; and means to adjust said control member in accordance with the various differences in the length of the lines, including means connecting the control member with the margin-setting stops, one of which connecting means constitutes a fulcrum for the control member; said control member adjusting means also including a manually operable setting member to adjust said connecting means transversely relatively to the longitudinal axis of the control member, whereby to rock the control member about its fulcrum; and a rack bar and gear in the connection between the setting member and the connecting means.

7. A device adapted to be used in connection with a typewriting machine having a carriage, including letter-feed mechanism for the carriage; means to vary the length of the feed movements of the carriage to justify the lines of writing to a desired uniform length; an actuating member to effect an additional movement of the carriage; adjustable margin-setting stops; a control member fulcrumed on one of said margin-setting stops, and connected to said actuating member for relative movement; means to adjust the control member according to the various differences in the length of the lines, and also according to the desired length of the uniform lines; and means to connect the control member with the other of said margin-setting stops; said adjusting means for the control member including a setting member to transversely adjust said connecting means to operate said control member about its fulcrum; and a locking means to prevent undesired displacement of said connecting means.

8. A device adapted to be used in connection with a typewriting machine having a traveling carriage, including letter-feed mechanism for the carriage, means to vary the length of the feed movements of the carriage to justify the lines of writing to a desired uniform length including: an actuating member to effect an additional movement of the carriage; a pair of individually adjustable margin-setting stops on the carriage; a control member fulcrumed on one of said margin-setting stops, and connected to said actuating member for relative movement; means to adjust the control member in accordance with various differences in the lengths of the lines to be justified, and also, according to the length of the desired uniform lines; and means to connect the control member and the remaining margin-setting stop; said adjusting means for the control member including a setting member to transversely adjust said connecting means, to rock the control member about its fulcrum; a locking mechanism to maintain the setting member in any of its adjusted positions; and a notched member cooperating with the locking mechanism to release the latter upon operation of the setting member.

ANDRÁS GOY.
